UNITED STATES PATENT OFFICE.

LOUIS LEHR, OF BRIGHTON HEIGHTS, NEW YORK, ASSIGNOR TO SIMON BRUNER, OF FAR ROCKAWAY, NEW YORK.

FINGER RING.

Application filed May 15, 1925. Serial No. 30,437.

To all whom it may concern:

Be it known that I, LOUIS LEHR, a citizen of the United States, and a resident of Brighton Heights, Staten Island, New York, have invented a new and useful Improvement in Finger Rings, of which the following is a specification.

This invention relates to finger rings and more particularly to so-called signet rings.

10 In the jewelry art certain types of finger rings are known generally as signet rings. These rings include a mount bearing an initial or other significant symbol in accordance with the desire of the individual owner.

15 Inasmuch as an initial or symbol is not a tangible element, the term "initial member" will hereinafter be used to indicate a removable member, either a cut-out initial, symbol or other device adapted to be held in a predetermined position with respect to a mount.

20 In view of the diversity of demands with respect to initials and designs and since rings are made in a plurality of sizes, it was incumbent upon a dealer to stock a large quantity of rings including the many sizes and initials in the hope of having the right size with the right initial when demanded.

25 This condition meant a large investment and was not always desirable to a retailer who would obviously have money tied up in a great number of articles the sale of which was speculative.

30 An object of the present invention is, therefore, to provide a ring of such construction that an initial or other symbol may be quickly and conveniently replaced by another, and especially in rings in which an initial is positioned upon a mounted stone.

35 Another object of the invention is to provide a ring in which a stone may be permanently mounted and an initial member removably attached thereto.

40 Another object of the invention is to provide a ring having a locking member for holding an initial or symbol member in place.

45 Another object of the invention is to pro-

vide a mount and a removable member constructed to be locked in a given position on the mount.

A further object of the invention is to provide a mount having a stone or facing permanently attached thereto and an initial member adapted for cooperation with the mount to hold the initial resiliently in contact with the stone.

50 Although the novel form of locking means of the present invention may be used to lock an initial member in any desirable style of stone mounting, it is herein shown and described in connection with a mount having a flat stone serving as a background for a cut-out initial.

55 The stone may be secured in position and provided with an aperture. The members to be mounted on the stone may be provided with projections or stems to extend through the aperture and means upon the mount engageable with the free end of the stem serve to hold the initial in place either for sale and use or for replacement by another initial.

60 The invention will be more fully understood by reference to the accompanying drawing in which

65 Fig. 1 shows a ring having an initial member attached thereto in accordance with the present invention

70 Fig. 2 is a top view of the ring shown in Fig. 1.

75 Fig. 3 is a sectional view of the ring taken on line III—III in Fig. 1.

80 Fig. 4 is an enlarged sectional view taken on line IV—IV in Fig. 2.

85 Fig. 5 is an enlarged sectional view taken on line V—V in Fig. 2, and

90 Fig. 6 is an enlarged top view of the ring with the stone removed to show the locking member.

95 The selected embodiment of the invention may, as illustrated, comprise a ring 10 having a mount 11 in which a flat stone 12 may be permanently secured in the usual manner. The mount may be of any configuration; the one shown being of parallelogram form and provided with a seat 13 for the

stone. Integral with the mount and extending transversely thereof is provided a cross-piece 14 having an aperture 15. The aperture 15 is positioned to coincide with a passageway 16 in the stone 12.

An initial member indicated as a whole by the numeral 17 may comprise a cut-out initial 18 having an extension or stem 19 disposed perpendicular to the underside of 10 the initial and secured in any suitable manner as by soldering or brazing.

The initial member may be positioned upon a stone 12 with the stem extending through the passage 16 and the aperture 15.

15 The end 21 of the stem may be provided with notches 22 to receive a locking member 23 slidable upon the cross piece 14. The locking member may comprise a plate having ears 24 bent about the cross-piece 14 to provide guides. A slot 25 of circular form, at one end, and having an elongated portion with straight parallel sides at the opposite end may be punched in the locking member.

20 The slot may be so disposed as to be registerable with the aperture 15 in the cross-piece 14. Thus the stem 19 may be positioned so that the end 21 thereof is disposed in the slot 25. A movement of the locking member 23 will then cause the edges of the

25 elongated portion of the slot to enter the notches 22 and secure the initial member. The initial member may be provided with a dowel pin 26 adapted to enter a hole 27 in the stone 12 to prevent relative movement 30 of the initial member on the face of the stone 12.

The locking member 23 serves to securely hold the initial in place and the cross-piece 14 may be relatively thin and resilient. Furthermore, the notches 22 may be cut at a 40 slight angle so that when the locking member engages with and is moved through the notches the initial member will be held with the initial positioned in firm contact with the stone 12.

45 Although the locking member may be actuated by hand, a tool 28 as indicated in dotted lines in Fig. 3 having a pointed end 29 may be provided to enter a hole 31 in the locking member to facilitate its movement to lock or unlock an initial member.

50 It will be appreciated that by reason of the present invention a dealer may be supplied with the usual line of rings of a reasonable number of different sizes having stones therein and he may have an assortment of initials, any one of which may be quickly and easily applied to a ring of the size selected by a purchaser, inasmuch as 55 the initial members may be applied to rings without regard to finger size.

60 By the provision of initial members applicable to a stone permanently secured in a mounting, the dealer avoids the cost of setting the stone or the danger of chipping its

edge as often occurs with highly brittle stones such as those of onyx or like material which are in vogue.

65 It will be further understood that although the present invention is shown applied to a finger ring the invention is of advantage with other mountings. For example, a bracelet, locket or other piece of novelty jewelry may employ a mount or holder for a stone on which it is desirable to dispose an initial. Such articles may be 70 of various designs and by reason of the present invention a dealer would be able to remove an initial from an article of one design and satisfy a customer by placing the initial on the article of a selected design. If instead of initials it is desirable to hold 75 other ornaments in place, the present construction will be found practicable whenever interchangeability is required.

80 Although a preferred embodiment of the invention is shown and described herein other modifications as above enumerated and others made without departing from the spirit and scope of the invention may occur 85 to those skilled in the art, but such modifications are contemplated as come within the scope of the appended claims.

90 What is claimed is:

1. A finger ring having a mount, a stone held in said mount, an initial member comprising a stem having transverse notches adjacent its exposed end, said stone having an aperture to receive the stem, an elongated cross-piece integral with said mount, and a member reciprocable along said crosspiece, guide portions integral with said member to embrace the crosspiece to retain the said member slidably thereon for engagement with the notches of said stem to hold the initial in fixed relation to said stone. 95

100 2. A finger ring having a mount, a stone having an aperture, said stone being secured in said mount, an initial member comprising an initial and a stem integral with said initial, said stem being provided with notches and disposed in said aperture, a resilient crosspiece integral with said mount, a member embracing said crosspiece and slidable thereon to engage with said notches to hold said initial in a given relation to 105 said stone.

110 3. A finger ring having a mount, a stone having an aperture and secured in said mount, an initial having a notched stem disposed in said aperture, a cross bar and a member having portions thereof embracing said cross bar, said member being slidable lengthwise of said cross bar for engagement with a notch of said stem to hold the initial 115 in a given relation to said stone. 120

125 4. A mount for a finger ring comprising an initial member having a stem adapted to be disposed in the mount, a resilient cross-piece and a lock member embracing said 130

cross-piece to engage with the stem of said initial member to hold the same in a given relation to the mount.

5. A mount for a finger ring comprising an initial member adapted to be disposed in the mount, a cross-piece, a slidable member embracing said cross-piece, extended portions on said member to retain the same

in movable relation to the cross-piece for locking said initial member in a given relation in the mount. 10

In testimony whereof, I have hereunto subscribed my name this 9th day of May, 1925.

LOUIS LEHR.
